(57) **CLAIM**

The ornamental design for a mountain bike stand, as shown and described.

DESCRIPTION

FIG. 1 is a top front perspective view of a mountain bike stand, showing my new design;

FIG. 2 is a front elevation view thereof;

FIG. 3 is a rear elevation view thereof;

FIG. 4 is a right-side elevation view thereof;

FIG. 5 is a left side elevation view thereof;

FIG. 6 is a left side sectional view taken along lines 6-6 from FIG. 2 thereof;

FIG. 7 is a top plan view thereof;

FIG. 8 is a bottom view thereof;

FIG. 9 is a bottom sectional view taken along lines 9-9 from FIG. 2 thereof;

FIG. 10 is a top sectional view taken along lines 10-10 from FIG. 2 thereof;

FIG. 11 is a bottom rear perspective view thereof; and, FIG. 12 is a rear perspective view shown in an environment of use.

The broken lines in FIG. 12 depict environmental subject matter of a bike, and tools that form no part of the claimed design.

The claimed design is shown with a symbolic break in its length the appearance of any portion of the article between the break lines forms no part of the claimed design.

1 Claim, 7 Drawing Sheets
